UNITED STATES PATENT OFFICE.

RALPH V. PALMER, OF ST. PAUL, MINNESOTA.

PISTON.

Application filed December 5, 1925. Serial No. 73,369.

To all whom it may concern:

Be it known that I, RALPH V. PALMER, a citizen of the United States, residing at St. Paul, in the county of Ramsey and State of Minnesota, have invented certain new and useful Improvements in Pistons, of which the following is a specification.

My invention relates to improvements in pistons for explosive type engines and the 10 main object is to provide a piston of certain construction and means for expanding the major part of the piston walls to provide take-up when a piston has become worn by its reciprocating movement, thus prolonging 15 the life of a piston.

In the accompanying drawing:

Fig. 1 is a side elevation of a piston of my improved form.

Fig. 2 is a bottom view of Fig. 1.

20 Fig. 3 is a vertical central section of the piston about as on line 3—3 in Fig. 2.

Fig. 4 is also a vertical section about as on line 4—4 in Fig. 2.

Referring to the drawing by reference 25 numerals, I have shown a preferred type of light-weight piston 5, having the usual solid web 6 at the upper and compression end of the piston. The barrel of the piston comprises an upper section 5^T with piston-ring retaining grooves 7 for rings 8, and a lower circular or ring section 5^L from which, at opposite sides, an apron 9 extends upwardly and terminates near head 5^T. The lower ring 5^L and aprons 9 are turned to approximately 30 the same diameter as head 5^T and said parts are provided with grooves 10 or so called oil grooves to spread lubricating oil on the piston and cylinder walls.

Between the opposite aprons 9 I provide 40 two horizontally spaced vertical walls 11 in which are bosses 12 bored for retaining the usual wrist pin 13 for the upper end of the connecting rod 14 (the latter shown dotted in Fig. 3). Said walls are cast integral with 45 and project downward from the head end 5^T leaving horizontal openings 15 (Figs. 3 and 4) between the walls 11 and ring 5^L.

50 16 are two slits cut longitudinally of the piston and extending from its lower end at diametrically opposite sides of the piston up to a horizontal slot 17 below head 5^T, thus dividing that part of the entire piston below head 5^T into two semi-circular aprons each 55 comprising one half of the opposite areas 9 and the adjacent half of ring 5^L. These two parts will hereinafter be termed the

aprons of the piston. These aprons are because of the cuts 16 capable of being expanded diametrically to a certain extent and thus take up wear caused by the reciprocating movement of the piston in the engine cylinder (not shown). It will be understood that my piston is cast with thin cylindrical walls below head 5^T.

18 are two segmental vertically disposed plates each with an outwardly directed flange 18^A at its upper end and adapted to rest on the piston wall at the lower edge of slot 17. The body of each plate therefore is suspended by its flange and normally engages the inner wall surface of the piston preferably to a line below the center of the ring 5^L. The two plates are thus diametrically opposite each other and by spreading them from each other the two aprons are 70 forced outwardly and enlarge the diameter of the said parts of the piston. This spreading is done as follows:

One plate 18 has an upper pair of parallel threaded rods 19 each suitably fixed as in a 80 boss 20 at the inner side of the plate. The opposite plate has two parallel tubular members 21 suitably fixed to the inner side and each registering horizontally with a rod 19 for slidable insertion of the latter into its bore. 22 is a nut on the threaded part of each rod 19 and adapted to bear against the inner side of tube 21. Thus by manipulating these nuts the threaded rods 19 are forced outwardly from the tubes and the 85 opposite plates 18 are forced apart and cause the aprons to spread. The lower parts of the plates 18 are likewise provided with a pair of rods 19, sleeves 21 and nuts 22 for spreading the lower parts of the aprons. It is obvious that one pair of rods 19 and 90 cooperating parts may be used in short types of pistons. As a rule the normal amount of spreading required is only a few thousandths parts of an inch and therefore the 95 diametral strain on the aprons is so slight as not to effect the solidity of the piston.

What I claim is:

1. A piston of the class described comprising a tubular body with a solid web at one end and open at the other end, wrist-pin retaining means intermediate said ends, said piston having two diametrically opposite horizontal slots and slotted longitudinally from the center of each slot to the open end of the piston and means for spreading the parts of the piston between said hori-

- zontal slots and the open end, said expanding means comprising mainly two segmental plates each with an upper outwardly directed flange adapted to engage in one of 5 the horizontal slots and the main body of each plate of a curvature to fit the inner surface of the tubular piston and extending approximately to the lower end of the piston.
- 10 2. The structure specified in claim 1, and a number of horizontally disposed spreading elements for said plates, each said element comprising a fixed tube suitably secured to one plate, a horizontally registering threaded rod suitably fixed to the opposite plate and adapted to be slidably

guided in the tube, and a nut on the threaded rod normally engaging the open end of the tube.

3. A piston comprising a tubular body 20 with a closed head end and slotted longitudinally below said head end to form a number of circularly arranged depending aprons, removable outwardly flanged means engaging horizontal slits in the walls of the piston and horizontally extensible means connecting said flanged means to expand the aprons diametrically simultaneously as set forth.

In testimony whereof I affix my signature.

RALPH V. PALMER.
